UNITED STATES PATENT OFFICE.

CLARENCE E. WRIGHT, OF CLEVELAND, OHIO, ASSIGNOR TO DAVID A. YODER, OF TOLEDO, OHIO.

REGISTERING APPARATUS FOR TELEPHONE-EXCHANGES.

No. 818,068.

Specification of Letters Patent.

Patented April 17, 1906.

Application filed January 19, 1905. Serial No. 241,876.

To all whom it may concern:

Be it known that I, CLARENCE E. WRIGHT, a citizen of the United States of America, and a resident of Cleveland, in the county of Cuyahoga and State of Ohio, have invented certain new and useful Improvements in Registering Apparatus for Telephone-Exchanges, of which the following is a specification.

My invention relates to improvements in registering apparatus for telephone-exchanges and the circuits therefor, and has for its object the provision of means whereby both the number of calls and the elapsed time an operator requires for connecting or disconnecting may be positively registered. Such means are found in the prior art involving the use of a clock, associated with a numerical indicator; but my invention resides in the provision of certain apparatus herein described and claimed and its association in the most advantageous manner, so that the desired result is directly arrived at, and the invention is made applicable to telephone-exchanges with but little or no alteration in the original installation beyond the addition of the associated apparatus herein set forth.

I will explain my invention in connection with the accompanying drawings, wherein—

Figure I is a side elevation of a combined relay and counting device. Fig. II is a similar view thereof indicating the same when the winding thereof is excited and the contact-springs are closed together. Fig. III is a front view of the counting train or mechanism actuated by said relay. Figs. IV, V, and VI are diagrammatic illustrations indicating the application of my improvement in different ways to telephone-exchanges. Fig. VII is a view of a pendulum circuit-interrupter of my invention adapted for use in the systems shown but not claimed herein. Fig. VIII is an enlarged view, in side elevation, taken from the opposite side and illustrating further details of the device of Figs. I and II; and Fig. IX is a diagram illustrating a telephone cord-circuit at an operator's position with my invention applied thereto.

Throughout each of the several figures of the drawings the same character of reference is employed to indicate similar parts.

In the structure shown in Figs. I to III and in Fig. VIII an electromagnet a is employed, which is adapted when excited to actuate the

armature b and its attached lever c . This lever is connected at its end by means of a short actuating-crank d with the counting-train e of compact and well-known construction. Two contact-making springs f, g are insulatingly mounted upon the frame of the electromagnet and may be employed to control an associated circuit, the insulating-stud h upon the lever-arm serving to actuate the springs into engagement when the armature is excited, as in Fig. II. A small retracting-spring e'' opposes the movement of the armature. I may say that although illustrating this device, and preferably employing it in carrying out my improvements, the same is not of my invention, and I lay no claim thereto. Throughout the description of the diagrams setting forth my improvements I will indicate such device or any equivalent thereof by the reference character r or r' , depending upon whether it be used as a number-indicating or timing device. My invention of course is applicable to multiple switchboards requiring a large number of operators; but I consider that brief reference thereto as applied in one of its forms to the cord-circuit at a single operator's position will assist materially in an understanding of the invention.

Referring first to the diagram of Fig. IX, A will be understood as representing the apparatus at a subscriber's telephone-station terminating electrically at the exchange in 85 the jack 5, with which is connected the line-relay 5', controlling the circuit through the line-signal lamp 5". The connecting-plugs of the operator's cord-circuit are designated, respectively, by 6 6', and the supervisory relay 7, associated with the answering-plug 6, controls the circuit at one point through the supervisory lamp 7'. p and p' will be recognized, respectively, as the line and supervisory pilot-relays controlling the circuits 95 through the pilot-signal lamps p^2 p^3 . S is a suitable source of current serving to operate the system shown. My invention of the same type diagrammatically indicated in simpler and more condensed form in Fig. IV 100 as applied to two operator's positions is shown in the lower portion of this Fig. IX specifically associated with the operator's cord-circuit of the diagram. Therein the manual switch s is adapted alternatively to 105 connect the registering apparatus r r' either

- with the line or the clearing-out pilot-signal relay. Associated in circuit with the registering device r' is a rotated electrical interrupter device i , which may be driven by electric motor or any suitable power connection at constant speed to supply a predetermined number of current impulses for each second of elapsed time when the circuit through the registering mechanism r' is closed. Accordingly the device r' when connected with its timed electrical interrupter i constitutes an electrically-actuated timing mechanism, the purpose of which will later be explained. The registering device r is merely a counting appliance. From the foregoing it will be understood that the relay p will be excited, thereby drawing up its armature and closing the controlled circuit whenever current flows through any line-signal lamp at the operator's position. Similarly, the relay p' will be excited to close its controlled circuit whenever the corresponding supervisory lamp is caused to light, all of which will be well understood by those skilled in the art.
- In Figs. IV to VI, I have indicated merely in a diagrammatic manner the application of my invention in somewhat varying forms to two operators' positions of a telephone-exchange. Referring either to Fig. IV or Fig. IX, S will, as before, be understood as a suitable source of current or battery. At p and p' I have indicated the usual pilot-relays for operating, respectively, the pilot-signals at each operator's position when a line-signal is actuated in the well-known manner and when the clearing-out signal is sent in. s is a switch which is adapted to connect the registering apparatus $r r'$ either with the line or the clearing-out pilot-signal relay. At i is indicated an interrupter rotated by electric motor or other suitable means at a constant rate of speed, say, so that four current impulses per second will be sent over any associated circuit when the same is closed. In the said diagram I have also employed an intermediate relay j , which is adapted to close circuit through the timing mechanism r' whenever the counting mechanism is actuated. In addition, upon the right-hand side I have shown an extra timing mechanism r' , connected in conductor x , which is adapted to be closed directly by the actuation of the counter-operating-mechanism r , its contact x' corresponding to one of the coacting springs $f g$ of the device of Figs. I and II. I have thus indicated the manner in which the circuit may be simplified somewhat by causing the counter-operating mechanism to serve as well in the capacity of an intermediate relay.
- In the embodiment of Fig. V each of the relays $p p'$ is provided with double contacts, as are the switches s'' , which enables the counting and timing devices to be connected directly in circuit without the intermediate re-

lay. This form is not so well adapted for existing telephone-exchanges, since the installation must be changed to provide this additional feature.

In the diagram of Fig. VI separate brushes i^2 are provided upon the interrupter, which lead to the different operator's positions, this being a construction adapted principally for small exchanges.

From the foregoing description of apparatus the operation will now be quite readily understood. Assuming that the switches s are manually moved into engagement with their left-hand contacts, the apparatus will then be in condition to indicate the number of calls and the time elapsing before the respective operators make the required connections. A call being initiated at the position shown on the right, Fig. IV, relay p will be energized, causing its contacts to close and closing circuit through conductor 1, the relay-contacts, switch s , conductor 2, the intermediate relay j , counting mechanism r , and to the other pole of the battery; also, from conductor 2, through the closed contacts of relay j , through the timing mechanism r' , conductor 3, the intermittently-closed interrupter i , and conductor 4 to the other pole of the battery. This causes the counting mechanism r to register one call upon its counting-train, while the timing mechanism is actuated by the intermittent current at the rate of four movements per second until the circuit is opened at the contact of the pilot-signal relay p by the operator inserting the plug for making the connection in accordance with the well-known manner. In the operator's position corresponding to the right-hand side of the diagram (shown in Fig. IV and in Fig. IX) I have indicated the manner in which the timing mechanism may be operated directly through the closure of a circuit by the counter-operating mechanism. Thus circuit would also be closed through the engaging contacts x' of the counter-operating mechanism, the connected timing mechanism r' , conductors x^2 , the interrupter i , and conductor 4 to the opposite pole of the battery. Either mode of operating the timing mechanism may be employed, and in this case the two timing devices diagrammatically shown would give identical indications. Where both devices $r' r''$ are used, one may be placed upon the chief operator's desk and one upon the monitor's, for example. It will be understood, of course, that the relay-contacts $f g$ are not required in the device of Fig. I when it is employed as a timing mechanism or when an intermediate relay is also provided no function for the circuit-closing springs then existing. If, on the other hand, the elapsed time for making disconnections should be desired, the switches s will be manually thrown to engage their right-hand contacts, where-

upon the connected system of registering apparatus and relays, will be placed under the control of the clearing-out pilot-relays p' . In the diagram of Fig. V the switch s' , having 5 two make-and-break contacts, as have the two pilot-relays, it is perfectly obvious that the counting and the timing mechanism may be placed directly in circuit with the respective contacts and are individually controlled 10 and actuated over their separate circuits to effect the same results reached in the system of circuits just described. In the system set forth in Fig. VI such results are likewise attained by employing separate brushes i^2 upon 15 the rotated interrupter i , and thereby actuating the respective timing devices r' upon the closure of their individual circuits. The purpose of this associated apparatus need only be briefly alluded to. Each operator's position 20 will be charged upon her counting mechanism r , or rather the registering-train thereof with the number of telephone-calls which are made at her position upon the switch-board. Inasmuch as the timing mechanism 25 r' registers successively each quarter-second or any desired definite time interval elapsing until she makes the called-for connection and as the total elapsed time is computed upon the counting-train, the efficiency of the operator 30 is readily ascertained from these two results. Similarly, the promptness with which she makes her disconnections is arrived at in the same manner merely by throwing the controlling-switch s to the right instead of to the left.

In Fig. VII, I have illustrated an accurate and simple circuit-interrupter which may be adopted for use in many cases, the same being positioned at i in the diagrams when thus employed. This device may be used in lieu of the rotated interrupters i , if desired, in small plants. In said figure I have shown the pendulum-bob k of a clock making two beats to the second, we will say. A metal frame l is carried upon the rear of said bob, mounting in turn the contact-screws l' . Pivotedly mounted within said frame is a loosely-hung tongue m , adapted to contact with one or the other of said screws l' at each 45 beat of the pendulum. Conductor n , which will be connected with one pole of the battery, is led to the insulated contacts o of this tongue, while conductor n' for completing the circuit is grounded upon frame l . The 50 swinging of the pendulum accordingly causes the circuit to be opened and closed four times per second and serves to transmit the necessary electrical impulses for actuating any connected apparatus, as the timing mechanism r' of my improved registering system. The foregoing device, however, is not adapted 55 for use in telephone systems of any considerable size and is not specifically claimed herein, being shown merely as an additional

means for opening and closing the circuit 65 through the electrically-actuated timing mechanism.

It may be well here to observe that although a pilot-signal relay controlled in common by a given group of signals at the operator's position preferably is availed of for controlling in turn the registering apparatus used in practicing my invention other suitable circuit-closing means may readily be employed in lieu of said relay.

Having now described the manner in which my invention may be put into practice, I desire to claim, and secure by Letters Patent, the following:

1. In apparatus of the class described, the combination with a controlling-circuit-closing device, of a source of current, an electrically-actuated counter, another electrically-actuated counter, and means for supplying interrupted current thereto and adapted to be 85 connected with the latter, substantially as set forth.

2. In registering apparatus for telephone-exchanges, the combination with a controlling-circuit closer at the exchange, of an electrically-operated counting mechanism, an electrically-operated timing mechanism and means for simultaneously connecting current with each upon the actuation of the controlling-circuit closer, whereby the signaled call 90 or disconnection and the elapsed time in responding thereto are both registered, substantially as set forth.

3. In registering apparatus for telephone-exchanges, the combination with a pilot-signal relay at the exchange, of an electrically-actuated counter, intermediate circuit-closing means, a timing mechanism adapted to be connected in circuit with the latter and with a source of interrupted current upon 100 the actuation of the relay, whereby both appliances are operated upon the actuation of the relay, substantially as set forth.

4. In registering apparatus for telephone-exchanges, the combination with the pilot-relays for the line-signals and for the clearing-out signals at an operator's position, of a switch controlling the circuit to either of said 110 relays, an electrically-operated counting and timing mechanism adapted to be connected in circuit therewith, whereby the elapsed time either for making connection or disconnection may be automatically indicated, substantially as set forth.

5. In apparatus of the class described, the combination with a source of current, of means for interrupting the same at definite time intervals, a controlling-relay at the operator's position of a telephone-exchange, an electrically-actuated counting mechanism, 120 another electrically-actuated counting mechanism, and intermediate contacts closed together upon the actuation of the counting

- mechanism connected in circuit to supply the interrupted current to the last-mentioned counting mechanism during the closure of the controlling-relay, substantially as set forth.
- 5 6. In a telephone-exchange, the combination with a controlling-relay corresponding to each operator's position, a source of current controlled thereby, an electrically-actuated counter, and another electrically-actuated counter corresponding to each operator's position, a suitable timing interrupter device, and means for simultaneously closing the circuits through the electromagnets of 10 the counting mechanisms upon the actuation of the controlling-relay, substantially as set forth.
- 15

7. In registering apparatus for operators' positions at telephone - switchboards, the combination with an automatically-actuated circuit opening and closing device, of a source of electric current controlled thereby, and associated to be connected in circuit therewith in separate branches, an electrically-actuated counter in one branch, and a 20 25 timed interrupter device and another electrically-actuated counter in the other branch, substantially as set forth.

Signed at Cleveland this 29th day of November, 1904.

CLARENCE E. WRIGHT.
